(57) **CLAIM**

The ornamental design for an automotive wheel as shown and described.

DESCRIPTION

FIG. 1 is a front, left perspective view of an automotive wheel, in accordance with an embodiment;

FIG. 2 is a front, right perspective view of the automotive wheel of FIG. 1;

FIG. 3 is a front view of the automotive wheel of FIG. 1;

FIG. 4 is a rear view of the automotive wheel of FIG. 1;

FIG. 5 is a right view of the automotive wheel of FIG. 1;

FIG. 6 is a left view of the automotive wheel of FIG. 1;

FIG. 7 is a top view of the automotive wheel of FIG. 1; and,

FIG. 8 is a bottom view of the automotive wheel of FIG. 1.

The evenly dashed broken lines shown in drawings are for the purpose of illustrating environmental structure and forms no part of the claimed design. The short dash long dash broken lines define the bounds of the design and forms no part of the claimed design.

1 Claim, 7 Drawing Sheets
